ARRANGEMENT IN RECEIPT-ISSUING MACHINES FOR THE MARKING OF TICKETS

Nils Evert Johan Ståhl, Stocksund, and Oscar Uno Larsson, Hagersten, Sweden, assignors to AB Almex, Stockholm, Sweden

Filed Sept. 13, 1960, Ser. No. 55,781

Claims priority, application Sweden Oct. 1, 1959

3 Claims. (Cl. 101—66)

The invention according to this patent application refers to a method for the marking of time cards, such as weekly or monthly cards for riding by trains, busses or other traffic means, by means of a receipt-issuing machine, which is so arranged that the elements intended for the issue of receipts are automatically disengaged, when a card is introduced into the machine, in connection with which the elements, when the card upon the marking of the same is removed from the machine, are automatically returned into operative positions to permit of being again utilized optionally either for the printing of receipts or the marking of cards. The arrangement for carrying the method into effect consists of a scanning member located at the opening intended for the introduction of cards and adapted to be actuated by the cards in consideration, which scanning member is arranged by means of motion-transmitting members to bring a counter roller adapted to be pressed against the receipt-issuing roller of the machine out of the operative position, in order thus to prevent the discharge of a receipt at the marking of cards.

The present invention relates to a modified form of embodiment of an arrangement for automatically disconnecting the machine elements intended for the issue of receipts at the marking of cards by means of a receipt-issuing machine according to claims 1, 2 and 3 of the Patent No. 2,945,432. The arrangement is principally distinguished by the feature that the counter pressure roller adapted to be pressed against the receipt-issuing roller of the machine is rotatably mounted on a double-armed lever, which is adapted by the actuation of the machine elements to swing through a certain swinging angle in every working cycle, in connection with which a scanning member adapted to be actuated by a card introduced into the machine is arranged to retain the lever in a certain swinging position in order thus to prevent the counter pressure roller from pressing against the receipt-issuing roller at the marking of cards.

An arrangement according to the invention and features characteristic of the same will be described hereinbelow and is illustrated with reference to the accompanying drawing. FIGS. 1 and 2 of the drawing are diagrammatic views of the arrangement. FIG. 3 shows the swingable lever and the scanning member actuating the same as combined with the stand of the machine.

In the drawing, 1 designates a plane or approximately plane stand member of the machine, which member is provided with an attachment for journals and the like for the arrangement of elements comprised in the machine, 2 denotes a receipt-issuing roller mounted on a journal 3, and 4 designates a strip actuated by said roller for the printing of receipts and tickets. A double-armed lever 6 is swingably arranged on a journal 5 secured in the stand member 1 in a plane approximately paralleling said stand member. Secured on one end portion of the lever 6 is a journal 7, on which is rotatably mounted a roller 8 adapted to be pressed against the receipt-issuing roller 2. The roller 8 is adapted to be pressed against the receipt-issuing roller 2 by means of a spring 9 actuating the lever 6. The lever 6 is provided with an arm 10 directed angularly to a longitudinally direction

2

thereof, an antifriction roller 11 being mounted on the end portion of said arm 10. 14 denotes a cam adapted to be rotated by means of a shaft 13, said cam being arranged when rotated to actuate the roller 11 in order thus to swing the lever 6 into a swinging position so adapted that the counter pressure roller 8 is brought into an inoperative position away from the receipt-issuing roller 2. The cam 14 is so combined with the manually or mechanically operated elements of the machine that the cam is caused to be rotated one revolution for every working cycle, besides which the cam is arranged to come to rest in a position to exert pressure against the antifriction roller 11 to swing the lever 6 through a certain swinging angle in order thus to bring the counter pressure roller 8 away from the operative position against the receipt-issuing roller 2.

15 designates a scanning member, which is rigidly connected to an axle 16 and a hook 17. The scanning member 15 and the hook 17 are swingably arranged on the stand member 1 by means of the axle 16. The housing 18 of the machine is provided with an opening 19 for the introduction of a card 20 for the purpose of marking the latter. Arranged immediately inside the opening 19 in the housing 18 is a screen 21, against the lower side of which screen the scanning member 15 is adapted to bear in the inoperative swinging position. 22 designates a spring combined with the hook 17 and the scanning member 15, said spring being arranged to swing the scanning member against the lower side of the screen 21.

Receipts to tickets printed on the strip 4 and issued by the roller 2 are severed by means of a knife 23 a conventional type. 24 denotes a typewriter ribbon arranged in a manner known per se, and 25 designates a control strip.

Receipts or tickets are printed from the lower side on the strip 4 by means of a printing means known per se and not shown in the drawing.

In the marking of a card 20 in the machine, the same is introduced, as shown in FIG. 1, through the opening 19 in the housing of the machine, said card then actuates the scanning member 15 and swings the same and the hook 17 rigidly connected with the member. Hereby the hook 17 is brought into such a position above the free end portion 26 of the lever 6 that the hook prevents the lever from swinging at the marking of the card. In the marking of a card, the counter pressure roller 8 will thus be prevented from pressing the receipt strip 4 against the issuing roller 2, which makes the latter inoperative and the receipt strip becomes stationary. In the marking of the card, the latter is located between the stationary receipt strip 4, and the typewriter ribbon 24, the printing hammers operating against the lower side of the card being then adapted with the receipt strip as a webbing, but without this being provided with any print whatsoever, to bring about the intended print or marking both on the card and on the control strip as well.

FIG. 2 shows the counter pressure roller 8 in the operative position against the receipt-issuing roller 2 in the printing of tickets and receipts.

We claim:

1. In a card marking and receipt issuing machine, a receipt issuing roller, a lever, means pivotally securing the central portion of said lever, a pressure roller rotatably mounted on one end of said lever, first spring means pivoting said lever urging said pressure roller against said receipt issuing roller, an arm extending from said lever, an anti-friction bearing supported roller rotatably mounted at the end of the arm extending from said lever, a cam rotated during each cycle of said card marking and receipt issuing machine, said cam in a rest position engaging the roller supported by the arm of said lever pivoting said lever against said first spring means moving said pres-

sure roller from against said receipt issuing roller, a hook pivotally mounted at the end of said lever opposite said pressure roller, second spring means pivotally urging said hook away from said lever, a scanning member fixed to said hook, said scanning member being engaged by a card inserted in said card marking and receipt issuing machine pivoting said hook to engage said lever preventing the rotation of said lever upon the rotation of said cam, said cam being rotated once during each cycle of said card marking and receipt issuing machine, said cam having a single raised portion, said raised portion of said cam being under said anti-friction roller when said cam is in a rest position, a guide screen, said guide screen guiding cards inserted into said card marking and receipt issuing machine against said scanning member, said scanning member resting against said guide screen, and a card inserted into said card marking and receipt issuing machine, said card passing between said guide screen and said scanning member thereby urging said scanning member away from said guide screen.

2. A card marking and receipt issuing machine comprising a frame, a receipt issuing roller supported by the frame, a lever located near the receipt issuing roller, means pivotally supporting said lever near the center thereof, said lever including an arm extending outward therefrom, near the center of the lever, a pressure roller rotatably mounted on the end of the lever near the receipt issuing roller, a first spring means attached to the lever, said first spring means being operative to normally urge the pressure roller toward the receipt issuing roller, a roller rotatably mounted at the free end of the arm of said lever, a cam mounted adjacent the roller on the arm of the lever, said cam being operative to move the pressure roller out of engagement with the receipt issuing roller, against the pressure of the spring means, said cam being rotated once during each cycle of the receipt issuing machine, an L-shaped hook pivotally supported adjacent

the end of said lever, opposite the pressure roller, said hook having means formed thereon operative to engage the lever, to prevent movement of the pressure roller toward the receipt issuing roller, second spring means attached to said hook normally urging the hook away from the lever, to permit movement of the lever and the pressure roller, means for permitting the insertion of a card into said machine, in a direction from the hook toward the receipt issuing roller, an angularly positioned guide screen located near the card to guide the card, a scanning member fixedly attached to said hook, a card inserted into said machine passing between the guide screen and the scanning member, the card being operative to engage the scanning member to tilt the scanning member and the hook attached thereto, thereby to prevent movement of the lever and the pressure roller supported thereby toward the receipt issuing roller, said cam having a single raised portion, the raised portion of the cam being located under the roller mounted on the arm of the lever, when the cam is in a rest position, said card being operative to urge the scanning member away from the guide screen, thereby to move the hook toward the lever, thereby locking the lever, with the pressure roller supported by the lever in a position free of the receipt issuing roller.

25 3. In combination with a card marking and receipt issuing machine, as in claim 2, a shearing mechanism located adjacent the receipt issuing roller, said shearing mechanism being operative to shear the strip fed by the receipt issuing roller to form individual receipts.
